UNITED STATES PATENT OFFICE.

WILFRED STAFFORD, OF LONDON, ENGLAND, ASSIGNOR OF ONE-HALF TO WILLIAM DAVIES, OF LONDON, ENGLAND.

DESK, TABLE, AND LIKE OFFICE FURNITURE.

1,385,233.

Specification of Letters Patent. Patented July 19, 1921.

Application filed November 23, 1920. Serial No. 426,029.

To all whom it may concern:

Be it known that I, WILFRED STAFFORD, a subject of the King of Great Britain, and a resident of London, England, have invented 5 new and useful Improvements in Desks, Tables, and like Office Furniture, of which the following is a specification.

This invention relates to desks, tables and like office furniture, and provides a desk or 10 table the top of which, or a part thereof, can be rotated to different positions in such a manner that in one position the upper surface of the table top is at a relatively low level so that it can be used to support, for 15 example, a typewriting machine at a height convenient to the comfort of an operator, or for other purposes where a desk with a rotatable top is desirable, and in another position the upper surface is raised to a convenient height for handwriting, book keeping and like uses of a desk or table. In this 20 last mentioned position the rotatable table top is raised to a position in which it is flush with the remainder or fixed part of the table 25 top, if there is any such fixed part. In moving from one position to the other the rotatable part of the table top is turned completely over so that if a typewriting or other machine is bolted or otherwise fixed to the 30 upper surface of the rotatable part of the table top when the latter is in its lower position, then, when the table top is turned over in being raised to its higher position, the said machine will be moved to a position 35 beneath the table top where it is out of the way. Means are provided for locking or retaining the rotatable table top in either of its positions of use.

In the accompanying drawings:—

40 Figure 1 is a perspective view of a desk or table embodying the said improvements, showing the rotatable part of the table top in one position of use, and

45 Fig. 2 is a similar view showing the rotatable part of the table top moved to another position.

Fig. 3 shows the improved desk or table in section on the line 3—3, Fig. 2.

As shown in the drawings, *a* is the rotatable part of a table top having metal lugs *b* fastened thereto in alinement on opposite sides of the said part and pivotally supported by studs *c* slidably mounted in slotted plates *d*, the holes in the lugs through which 55 the studs *c* pass being off-set from one face

of the part *a*. In the position in which it is shown in Fig. 1, the part *a* is at a lower level than the fixed part *e* of the table top and conveniently disposed to support, for example, a typewriting or other machine *f* 60 at a height convenient for use. The rear edge of the part *a* is held between battens *g*—*g'* to prevent this part from tilting. Within the plates *d* springs *h* may be provided to press the studs *c* toward the rear 65 ends of the slots in the plates, and, if desired, a latch or similar fastening *i* may be provided to prevent the said part *a* from being accidentally drawn forward.

When such latch, if provided, is released 70 the part *a* can be drawn forwardly against the thrust of the springs *h* until the rear edge is clear of the battens *g*, *g'*. The part *a* can then be rotated on the studs *c* so that it is raised by reason of the off-set arrangement of the lugs *b*, to the level of the fixed part *e* and maintained in this position by pushing it rearwardly until its rear edge is between the battens *g'*, *g*². In this position 75 the upper surface of the part *a* is flush with the fixed part *e* the two parts together providing an ordinary flat table top and the machine *f* is suspended from the under surface of the part *a* where it is out of the way of a user of the table. The latch above referred to may be arranged to retain the table top in this position also.

In the construction shown in the drawing, panels *j* are provided inclosing the space in which the machine *f* is suspended when the 90 part *a* is in the position shown in Fig. 2, and drawers *k* are provided beneath the fixed part *e*.

What I claim is:—

1. A desk comprising a rotatable top part, 95 lugs secured to the said top part and having stud receiving holes formed therein in alinement and offset from one surface of the said top part, a top supporting part, slotted plates secured to the said top supporting part, studs slidably carried in the slots in the said plates and extending into the holes in the said lugs to form pivotal supports therefor, springs urging the said studs toward the ends of the slots and battens carried by the top supporting part forming a slot to receive one edge of the top part.

2. A desk comprising a rotatable top part, lugs secured to the said top part and having stud receiving holes formed therein in aline- 110

ment and offset from one surface of the said top part, a top supporting part, slotted plates secured to the said top supporting part, studs slidably carried in the slots in 5 the said plates and extending into the holes in the said lugs to form pivotal supports therefor, and battens on the top supporting part forming upper and lower slots to alternately receive one edge of said top part when 10 in raised and lowered position.

3. A desk comprising a rotatable top part, lugs secured to the said top part and having stud receiving holes formed therein in alignment and offset from one surface of the said 15 top part, a top supporting part, slotted

plates secured to the said top supporting part, studs slidably carried in the slots in the said plates, and extending into the holes in the said lugs to form pivotal supports therefor, a plurality of battens carried by 20 the top supporting part and forming slots to receive one edge of said top part when in raised and lowered position, and a latch to retain said top part in engagement with either of said slots.

WILFRED STAFFORD.
